(57) **CLAIM**

The ornamental design for a fixed carbine stock, as shown and described.

DESCRIPTION

FIG. 1 is a right side elevation view of a fixed carbine stock attached to a firearm showing my new design;

FIG. 2 is a right, front, bottom perspective view of the fixed carbine stock of FIG. 1.

FIG. 3 is a left, rear, bottom perspective view of the fixed carbine stock of FIG. 1 with the firearm omitted;

FIG. 4 is a right side elevation view of the fixed carbine stock of FIG. 1;

FIG. 5 is a left side elevation view of the fixed carbine stock of FIG. 1;

FIG. 6 is a rear elevation view of the fixed carbine stock of FIG. 1;

FIG. 7 is a front elevation view of the fixed carbine stock of FIG. 1;

FIG. 8 is a top plan view of the fixed carbine stock of FIG. 1;

FIG. 9 is a bottom plan view of the fixed carbine stock of FIG. 1; and,

FIG. 10 is a right, front, bottom perspective view of the fixed carbine stock of FIG. 1 with an alternate embodiment of an adapter shown in phantom lines.

The broken lines showing portions of the design in all figures is included for the purpose of illustrating environment and unclaimed features and forms not part of the claimed design.

1 Claim, 8 Drawing Sheets
